UNITED STATES PATENT OFFICE.

GEORGE J. WEBER, OF KANSAS CITY, MISSOURI.

GAS-PRODUCER.

No. 879,505.

Specification of Letters Patent.

Patented Feb. 18, 1908.

Application filed February 9, 1905. Serial No. 244,940.

To all whom it may concern:

Be it known that I, GEORGE J. WEBER, a citizen of the United States, residing at Kansas City, in the county of Jackson and State 5 of Missouri, have invented certain new and useful Improvements in Apparatus for Producing Gas and Power, of which the following is a specification.

My invention relates to improvements in 10 apparatus for producing gas and power.

It relates particularly to the class of apparatus in which the power is produced in an engine of the explosive type driven directly by the products of combustion drawn by the 15 engine from a gas producer, burning fuel such as charcoal, wood, coal or coke.

The object of my invention is to provide an apparatus by which the tarry and not easily volatilized substances formed in the gas producer may be decomposed and converted with 20 the other gaseous products into an explosive compound used in running the engine, thus effecting the production of a gas of high efficiency for running the engine.

25 My invention provides further means by which the depth of the ignited fuel in the producer may be varied in accordance with the fuel employed so that a relatively large amount of carbonic oxid may be produced 30 therefrom.

My invention provides further, the introduction between the casing of the producer and the refractory lining therein of a heat insulating medium which conserves the heat 35 and protects the metal wall of the producer chamber.

40 My invention provides still further, a producer chamber in which the fuel is burned at atmospheric pressure and which has in the chamber a gas superheating device located above the ignited fuel and heated to incandescence thereby, whereby the tarry and not easily volatilized substances are decomposed.

45 My invention provides further, novel means for subdividing and superheating the products of combustion within the producer chamber, together with means for introducing steam and air into contact with the superheated products whereby steam is decomposed and a large supply of hydrogen and carbonic oxid is produced.

50 My invention provides further, a fuel reservoir in the explosive force of the producer chamber and means whereby the distance 55 between the discharge end of the fuel reser-

voir and grate or fuel support of the producer may be varied to suit the fuel employed.

My invention provides further, means for retaining the fuel reservoir at a relatively low temperature, thus preventing overheating of 60 the fuel held therein and preventing coking or bridging of the fuel in the reservoir.

My invention provides further, other novel features hereinafter fully described and claimed.

65 In the accompanying drawings, Figure 1 is a central vertical sectional view of the gas producer and part of the engine connected therewith. Fig. 2 is a plan view of the support for the baffle plates. Fig. 3 is a horizontal sectional view taken on the dotted line *a*—*b* of Fig. 1. Fig. 4 is a horizontal sectional view taken on the dotted line *c*—*d* of Fig. 1. Fig. 5 is a vertical sectional view of 70 the lower part of the fuel reservoir, its lateral 75 wings and the baffle plate support.

75 Similar characters of reference denote similar parts.

80 1 denotes the tubular vertical casing of the gas producer provided with a closed bottom plate 2, and a horizontal top plate 3. In the casing is a transverse fuel support comprising a horizontal plate 4 having a central hole and supporting the grate bars 5. The casing is 85 lined preferably with fire brick or clay 6, supported by the plate 4. Intermediate the lining 6 and the casing 1 is a lining 7, preferably of asbestos or mineral wool and forming a heat insulating medium between the casing 1 and the burning fuel. The lining 7 prevents 90 radiation of heat and protects the metal casing from injury thereby. In the upper end of the casing is a vertical movable horizontal plate 8, suspended by two vertical bolts 9 extending through openings provided therefor 95 in the top 3. Two nuts 10 are mounted respectively on the upper ends of the bolts 9 and rest on the top of the plate 3. A reservoir tube 11 extends vertically downward from the plate 8 and is vertically movable therewith. Said tube 11 is disposed in alignment with a fuel opening 12 in the plate 3.

100 Two diametrically opposite vertical wings 13 are provided on the reservoir 11 and extend from the plate 8 to a horizontal ring 14 secured to the lower end of the reservoir and provided with radial arms 15. On the arms 15 are mounted in criss-cross manner several series of baffle plates 16, which baffle plates 105 form a superheating device between which 110

879,505

the gaseous products of combustion pass. A mass of carbonaceous material 17 may be placed upon the upper row of baffle plates. A tube 18 extends vertically from the plate 8 through the top plate 3. Through this tube the baffle plates 16 and the material 17 may be inserted. A cover 19 is used to close the upper end of the tube 18. To retain the reservoir 11 at a relatively low temperature 10 the side thereof adjacent the baffle plates 16 has an asbestos lining 20. The opposite side of the reservoir is provided with a water jacket formed by a vertical curved plate 21 extending between the ring 14 and the plate 15 8 and between the two wings 13. Between the reservoir and the curved plate 21 is a semi-circular space 22 in which a cooling fluid such as water may be introduced through a vertical tube 23 having its lower end secured 20 to the plate 8 in a hole directly above the space 22 and which is slidable in a vertical hole in the plate 3. An opening is provided in the casing 1 below the grate bars 5 for the admission of air. A closure 24 mounted on 25 the casing 1 is employed to close said opening.

25 denotes a steam conductor leading from a suitable boiler, not shown, to and through the casing 1 below the grate bars 5. A valve 26 in said conductor may be employed to 30 regulate the amount of steam introduced below the grate bars.

27 is a conductor leading upward from the conductor 25 and having two discharge outlet pipes 28 and 29 disposed one above the other and extending through the casings 1 35 and linings 6 and 7. The outlet 29 is located preferably opposite the plate 16 and the upper outlet 28 opposite the material 17. Two valves 30 and 31 control respectively the 40 passage of steam through the outlets 28 and 29. Intermediate the outlets 28 and 29 is an air inlet 32 having a valve 33.

34 denotes the cylinder of an ordinary explosive engine and 35 a piston located therein. 45 A gas outlet comprising a conductor 36 connects the cylinder 34 with the producer chamber at a point preferably above the material 17. The conductor 36 is provided with an inlet tube 37 having a valve 38 which 50 controls the admission or air to be drawn in and mixed with the producer gas passing through the conductor 36.

In operating my invention fuel is inserted 55 through the opening 12 and reservoir 11 and deposited upon the grate 5. The closure 24 is then adjusted to admit air and the fuel ignited. Steam is then admitted through the conductor 25, past the valve 26. The engine piston 35 is then moved to draw into the 60 cylinder 34 by suction, through the conductor 36, the gaseous products of combustion and the air to be mixed therewith. The mixed gas and air is exploded in the ordinary manner, after compression, thus imparting 65 movement to the piston. The gaseous pred-

ucts of combustion will heat the baffle plates 16 and carbonaceous material 17 to a state of incandescence which will decompose the tarry gases undecomposed in the burning fuel. When the baffle plates 16 are heated to incandescence the valves 30, 31 and 33 are regulated to admit proper proportions of steam and air, which steam and air will become superheated, the steam uniting with carbon to form carbonic acid and carbonic acid gas. Some of the air entering through inlet pipe 32 will have its oxygen unite with the material 17 to form additional carbonic acid. In order that the greatest relative quantity of carbonic acid may be produced, 70 the depth of the ignited portion of the fuel, which is that lying between the lower end of the reservoir 11 and the plate 4, must be regulated to suit the fuel used. To do this the nuts 10 are turned so as to raise or lower the 75 reservoir 11. The proper adjustment for any given fuel may be ascertained by trial.

Having thus described my invention, what I claim and desire to secure by Letters Patent is:—

1. In a gas producer, the combination with the combustion chamber provided with an inlet for air and an outlet for the products of combustion, of a gas superheating mechanism vertically adjustable in the chamber intermediate the said inlet and outlet. 90

2. In a gas producer, the combination with the combustion chamber provided with an inlet for air, and an outlet for the gaseous products of combustion, of a series of baffle plates vertically adjustable in the chamber intermediate said inlet and outlet. 100

3. In a gas producer, the combination with the combustion chamber provided with an inlet for air and an inlet for steam, and having a fuel support located above said inlets, and an outlet for gaseous products of combustion located above the fuel support, of a vertically adjustable superheating mechanism located above the said fuel support 110 and below the said outlet and in said combustion chamber. 105

4. In a gas producer, the combination with the combustion chamber provided with a fuel support, inlets for air and steam disposed below said support, an outlet for gaseous products of combustion located above said support, and baffle plates vertically adjustable intermediate the said outlet and said support. 115

5. In a gas producer, the combination with a combustion chamber provided with a fuel support, of a fuel reservoir disposed above said support, superheating means carried by said reservoir and means by which the distance between the support and reservoir may be varied. 125

6. In a gas producer, the combination with a combustion chamber provided with a fuel support, of a fuel reservoir disposed 130

above the said support, superheating means carried by said reservoir and means for vertically adjusting the reservoir.

7. In a gas producer, the combination 5 with a combustion chamber having a fuel support, an inlet for air below said support and an outlet for gaseous products above said support, of a fuel reservoir in said chamber above said support and with its discharge end below said outlet, and vertically 10 adjustable gas superheating device located in said chamber intermediate said support and said outlet.

8. In a gas producer, the combination 15 with a combustion chamber, having a fuel support, an inlet for air and an outlet for the gaseous products disposed respectively below and above said support, of a fuel reservoir in said chamber above said support, 20 means for varying the distance between said reservoir and said support, and a superheating device carried by said reservoir and located intermediate the lower end of said reservoir and said outlet.

25 9. In a gas producer, the combination with a combustion chamber having a fuel support, an air inlet and a gas outlet located respectively below and above said support, of a vertically adjustable fuel reservoir in said chamber above said support, and a gas superheating device carried by said reservoir and located intermediate said support and said outlet.

30 10. The combination with a combustion chamber having a fuel support, an air inlet and a gas outlet disposed respectively below and above said support, of a fuel reservoir vertically adjustable in said chamber above said support, and baffle plates carried by said 40 reservoir and located intermediate the support and outlet.

35 11. The combination with a combustion chamber having a fuel support, an air inlet and a gas outlet disposed respectively below and above said support, of a vertically adjustable fuel reservoir in said chamber above said support, and a gas superheating device vertically movable with said reservoir and intermediate the outlet and support.

45 12. The combination with a combustion chamber having a fuel support, an air inlet and a gas outlet disposed respectively below and above said support, of a vertically adjustable fuel reservoir in said chamber above said support, and a gas superheating device vertically movable in said chamber intermediate the support and outlet.

50 13. The combination with a combustion chamber having a fuel support, an air inlet and a gas outlet located respectively below and above said support, of a vertically adjustable fuel reservoir located in said chamber above support, and a plurality of baffle plates in said chamber and vertically adjustable 60 intermediate said support and said outlet.

14. The combination with a combustion chamber having a fuel support, an air inlet, and a gas outlet located respectively below and above said support, of a vertically adjustable fuel reservoir in said chamber above 70 said support, and a plurality of baffle plates in said chamber and vertically adjustable with said fuel reservoir.

15. The combination with a combustion chamber having a fuel support, an air inlet and gas outlet located respectively below and above said support, of a fuel reservoir in said chamber above said support, a gas superheating device located intermediate the outlet and said support, and a heat insulating medium located between said reservoir and said superheating device.

75 16. The combination with a combustion chamber having a fuel support, an air inlet and gas outlet, of a fuel reservoir vertically adjustable in said chamber, and a series of baffle plates intermediate the reservoir and the inner wall of the chamber and above the support.

80 17. The combination with a combustion chamber having a fuel support, an air inlet and gas outlet, of a fuel reservoir in said chamber above said support, a series of baffle plates intermediate the reservoir and the inner wall of the chamber, and intermediate 95 the outlet and support, and means for vertically adjusting the reservoir and baffle plates.

90 18. The combination with a combustion chamber having a fuel support, an air inlet and a gas outlet, of a fuel reservoir in the chamber above the support, a series of baffle plates intermediate the reservoir and the inner wall of the chamber and intermediate 100 the outlet and said support, and a heat insulating medium intermediate the baffle plates 105 and the reservoir.

110 19. The combination with a combustion chamber having a fuel support, an air inlet and a gas outlet, of a fuel reservoir in said chamber above said support, a series of baffle plates intermediate the reservoir and the inner wall of the chamber and intermediate the outlet and said support, a heat insulating medium intermediate the baffle plates and the reservoir, and means for varying the 115 distance between the reservoir and support.

120 20. The combination with a combustion chamber having a fuel support, an air inlet and gas outlet, of a fuel reservoir vertically adjustable in said chamber above said support, a series of baffle plates intermediate the reservoir and inner wall of the chamber, and a heat insulating medium intermediate the baffle plates and the reservoir.

125 21. The combination with a combustion chamber having a fuel support, an air inlet and gas outlet, of a fuel reservoir vertically adjustable in said chamber above said support, a gas superheating device carried by said reservoir and intermediate said reservoir 130

48. GAS, HEATING & ILLUMINATING

and the inner wall of the chamber and intermediate the support and said outlet, and means for introducing a fluid into the chamber above said support and in contact with 5 said superheating device.

22. The combination with a combustion chamber having a fuel support, an air inlet and a gas outlet, of a fuel reservoir in said chamber above said support, means for 10 varying the distance between said reservoir and the support, a gas superheating device carried by said reservoir and located intermediate the reservoir and the inner wall of the chamber and intermediate the support 15 and outlet, and means for introducing a fluid into the chamber in contact with said superheating device.

23. The combination with a combustion chamber having a fuel support, an air inlet 20 and gas outlet, of a fuel reservoir in said chamber above said support, a gas superheating device intermediate the reservoir and the inner wall of the chamber, and intermediate the outlet and support, and means 25 for introducing steam and air into said chamber in contact with said superheating device.

24. The combination with a combustion chamber having a fuel support, an air inlet 30 and gas outlet, of a fuel reservoir vertically adjustable in said chamber above said support, a gas superheating device carried by said reservoir and located intermediate the reservoir and the inner wall of the chamber, 35 and intermediate the support and outlet, and means for introducing steam and air into said chamber in contact with said superheating device.

25. The combination with a combustion 40 chamber having a fuel support, an air inlet and gas outlet, of a fuel reservoir in said chamber above said support with its discharge end below said outlet, a gas superheating device located intermediate the reservoir and inner wall of the chamber, and intermediate the lower end of the reservoir and the outlet, and means for introducing a fluid into said chamber intermediate the outlet and the discharge end of the reservoir and 50 in contact with said superheating device.

26. The combination with a combustion chamber having a fuel support, an air inlet and gas outlet, of a fuel reservoir in said chamber above said support and having its 55 discharge end below said outlet, a gas superheating device located intermediate the reservoir and the inner wall of the chamber and intermediate the support and outlet, means for introducing steam into said chamber below said reservoir, and means for introducing steam and air into said chamber intermediate the outlet and the discharge end of the reservoir.

27. The combination with a combustion

chamber having a fuel support, an air inlet 65 and gas outlet, of a vertically adjustable fuel reservoir in said chamber above said support, a gas superheating device intermediate the reservoir and the inner wall of the chamber, and intermediate the outlet and 70 said support, means for introducing steam into the chamber below the discharge end of the reservoir, and means for introducing steam and air into the chamber intermediate the outlet and the discharge end of the reservoir 75 and in contact with the superheating device.

28. The combination with a gas engine cylinder and piston, of a combustion chamber having a fuel support, an air inlet and an 80 outlet discharging into said cylinder, and means for varying the depth of ignited fuel in the chamber.

29. The combination with a gas engine cylinder and piston, of a combustion chamber having a fuel support, an air inlet and an 85 outlet discharging into the cylinder, a gas superheating device located in the chamber intermediate the support and outlet, and means for varying the depth of ignited fuel 90 in the chamber.

30. The combination with a gas engine cylinder and piston, of a combustion chamber having a fuel support, an air inlet and gas outlet discharging into said cylinder, a 95 gas superheating device located in said chamber intermediate said support and outlet, means for varying the depth of ignited fuel in said chamber, and means for introducing a fluid into the chamber intermediate the 100 ignited fuel and the outlet.

31. The combination with a gas engine cylinder and piston, of a combustion chamber having a fuel support, an air inlet and gas outlet discharging into said cylinder, 105 means for varying the depth of ignited fuel in the chamber, a gas superheating device located in said chamber intermediate the support and the outlet, means for introducing a fluid into the chamber intermediate the 110 outlet and the ignited fuel, and means for introducing steam into the chamber below the ignited fuel.

32. The combination with a gas engine cylinder and piston, of a combustion chamber having a fuel support, an air inlet and gas outlet discharging into the cylinder, a fuel reservoir in the chamber, a gas superheating device located in the chamber intermediate the discharge end of the reservoir 120 and the outlet, means for introducing a fluid into the chamber intermediate the discharge end of the reservoir and the outlet, and means for introducing steam into the chamber below the discharge end of the reservoir.

33. The combination with a gas engine cylinder and piston, of a combustion chamber having a fuel support, an air inlet and

gas outlet discharging into said cylinder, a fuel reservoir in said chamber, and means for varying the distance between said support and reservoir.

- 5 34. The combination with a gas engine cylinder and piston, of a combustion chamber having a fuel support, an air-inlet and gas outlet discharging into said cylinder, a fuel reservoir in said chamber, means for 10 varying the distance between said support and the reservoir, and a gas superheating device located in the chamber intermediate the support and outlet.

- 15 35. The combination with a gas engine cylinder and piston, of a combustion chamber having a fuel support, an air inlet and gas outlet discharging into said cylinder, a fuel reservoir in said chamber, means for varying the distance between the reservoir 20 and support, means for introducing a fluid into the chamber intermediate the discharge end of the reservoir and the outlet, and means

for introducing steam into the chamber below the discharge end of the reservoir.

36. The combination with a gas engine cylinder and piston, of a combustion chamber having a fuel support, an air inlet and gas outlet discharging into said cylinder, a fuel reservoir in said chamber, means for varying the distance between the support and reservoir, a gas superheating device located in the chamber intermediate the support and outlet, means for introducing steam into the chamber below the discharge end of the reservoir, and means for introducing a fluid 30 35 into the chamber intermediate the outlet and the discharge end of the reservoir.

In testimony whereof I affix my signature in presence of two witnesses.

GEORGE J. WEBER.
